PAUL M. KRÈE AND FERNAND DAUTEUIL, OF NEW YORK, N. Y.

AUTOMATIC STOP AND START FOR PHONOGRAHS.

1,339,203.

Specification of Letters Patent.

Patented May 4, 1920.

Application filed July 28, 1919. Serial No. 313,752.

To all whom it may concern:

Be it known that we, PAUL M. KRÈE and FERNAND DAUTEUIL, both citizens of the United States, both residents of the city, county, and State of New York, have invented a new and Improved Automatic Stop and Start for Phonographs, of which the following is a full, clear, and exact description.

10 Our invention relates to a mechanism for automatically starting and stopping the movement of a record and it has reference more particularly to a device comprising an electromagnetic mechanism, the currents of 15 which are controlled by the record.

It is also the object of this invention to provide a device of the class mentioned which can be easily attached to any phonograph on the market.

20 A practical embodiment of our invention is illustrated in the accompanying drawings forming part of the specification, in which similar characters of reference indicate corresponding parts in all the views.

25 Figure 1 is a fragmentary top plan view of a phonograph equipped with our device.

Fig. 2 is an axial section through a phonograph equipped with our device.

30 Fig. 3 is a detailed illustration of the electromagnetic control of the brake mechanism, and

Fig. 4 is an electrical diagram showing the 35 circuits of the device.

Referring to the drawings 5 is a turn table 35 forming the support for a record 6. The turn table is provided with a sleeve 7 which is free to slide axially in the table and which has the necessary means for engaging the driving shaft 8 of the motor 9 of the phonograph. The sleeve 7 is also free to slide on 40 the driving shaft 8. The end of the sleeve 7 extending into the case of the phonograph is engaged with a forked end 10 of an arm 11 pivotally mounted within the case of the phonograph, as shown it is being pivoted on the motor 9. A tension spring 12 is provided at the other end of the arm so that normally the forked end tends to raise the sleeve above the surface of the table 5. The 45 tension spring 12 being of such a resistance that the weight of the record 6 is sufficient to depress the sleeve into the position shown in Fig. 2, that is, flush with the table. 50

The forked end of the arm 11 is adapted

to engage a stationary contact 13 in its downward movement and close a circuit to electromagnets 14 mounted in a suitable frame 15. (See Fig. 3.) The forked end of the arm 10 is insulated from the sleeve by a suitable member 13'. The return movement 60 of the forked end 10 of the arm 11 does not close a circuit for an insulating member 16 is provided to prevent contact. The circuit being closed only for a short interval of time is sufficient to energize the magnet and 65 operate the yielding bar 17 and cause the displacement of the bell crank arm 18 which carries a brake member 19 (see Fig. 3) and disengage or free the table and allow the 70 motor 9 of the phonograph to start the rotation of the table.

The displacement of the bell crank lever 18 must only be very slight for a spring 20 aids further movement of the lever as soon as the points of connection of the spring 20 75 are not in the line with the pivot of the lever. The electromagnets 14 are supplied with current from a battery 21 located in a suitable place within the case of the phonograph and connected by wires 22 and 23 as best 80 shown in the diagram in Fig. 4.

The record 6 carries a metallic segment 24 in proximity of the end of the sound groove of the record. This segment is grounded by its engagement with the driving shaft 8 of 85 the motor, the tone arm 25 being mounted on the wooden case of the phonograph which is insulated. It is connected by means of a wire 26 to a source of electricity 27. The same source is also connected by a wire 28 to 90 a set of coils 29, mounted on the frame 15 to face the coils 14. These electromagnets influence the yielding bar 17 in a direction opposite to that of the coils 14.

The metallic needle carried by the stylus 95 bar coming in contact with the segment 24 will close the circuit of the source 27 causing the electromagnets 29 to be energized thereby attracting the bar 17, in consequence applying the brake against the table 5 and 100 stopping the record. The brake will remain in engagement with the turn table until a new record or the same record will be replaced on the table so as to cause an engagement between the forked end 10 with the 105 contact 13 to operate the brake in the manner previously mentioned. The circuit will be broken by the inertia of the table carry-

ing the segment 24 part of the needle, while the brake will remain applied against the table 5 under the action of the spring 20.

We claim:—

- 5 1. In a phonograph having a revolving table and a brake mechanism for same, of a sleeve mounted to move axially in the table, yielding means for resisting the movement of the sleeve and so arranged that said yielding means are adapted to be depressed when a record is placed on the table, electromagnetically operable means for operating the brake mechanism to apply or release the same, and means operable by the movement 10 of the yielding means for controlling the circuit to the electromagnetic means.
2. In a talking machine a turn table having a sleeve adapted to move axially, said sleeve having means for engaging the driving shaft of the phonograph movement to turn therewith and to slide on said shaft, a pivotally mounted arm having one end in engagement with said sleeve, a tension spring associated with the other end of said 15 arm so that normally said arm tends to move said sleeve above the table, electromagnets for operating the brake mechanism, an open circuit for the electromagnets, and a contact in said circuit operable by the arm 20 in its downward movement only, to close the circuit, to affect the electromagnets, to release the brake, to allow the table to turn substantially as and for the purpose set forth.
3. A phonograph comprising a table mounted to revolve, a brake mechanism for said table, electromagnetic means to move said brake into engagement with the table, 25

electromagnetic means for disengaging the brake from the table, open circuits for said electromagnetic means, means movable axially relative to the table for closing the circuit to the electromagnets, means for disengaging the brake from the table, and means adapted to be carried by the record 40 and coöperate with the needle of the sound box for closing the circuit of the electromagnets to bring the brake into engagement with the table.

4. In a phonograph a table mounted to 50 revolve, a sleeve in said table mounted to move axially and having means for engaging the driving shaft of the motor of the phonograph and to slide thereon, yielding means normally tending to maintain the sleeve above the table, said yielding means being adapted to allow the displacement of said sleeve when a record is placed on the table, a pair of oppositely disposed electromagnets, a yielding bar adapted to be influenced by said electromagnets, a brake mechanism for the table connected to said yielding bar, an open circuit for one of said electromagnets, means for closing the said circuit operable by the downward movement 55 of the sleeve, whereby said brake mechanism is operated so as to disengage the table, an open circuit for the other electromagnets and means carried by the record and the tone arm for closing the circuit to cause 60 said electromagnet to influence the yielding bar to bring the brake into engagement with the table.

PAUL M. KRÈE.
FERNAND DAUTEUIL.
